FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FRAME.

1,200,479.

Specification of Letters Patent. Patented Oct. 10, 1916.

Application filed April 25, 1914. Serial No. 834,318.

To all whom it may concern:

Be it known that I, FRANZ A. FULLER, a citizen of the United States, residing in the city of Newark, in the county of Essex and State of New Jersey, have invented certain new and useful Improvements in Bag-Frames, of which the following is a full, clear and exact description, such as will enable others skilled in the art to which it pertains to make, construct, and use the same, reference being had to the accompanying drawings, and to numerals of reference marked thereon, forming a part of this specification.

This invention has reference to improvements in the manufacture of frame sections for bags and purses, and especially for traveling, chatelaine and similar bags, and the invention has for its principal object, to provide a simple bag frame section comprising a main body and downwardly extending hinge members, said main body being provided with a chambered portion extending upwardly from said main body and to which the lock is secured.

In the construction of frame sections, it has become necessary to make the same as narrow as possible, with the resulting annoyance that with many forms of locks now in use, it has been necessary to cut out the inlay to which the fabric of the bag body is secured, to such an extent as to weaken the same, and further, the main body portion of the bag frame section to which the lock is secured being narrow, causes great inconvenience in securing the lock thereto, in many instances distorting the frame sections to such an extent as to render them useless.

In order to eliminate these evils, and overcome these objections, I have devised a new frame section, which provides the necessary strength at that point where the lock is secured thereto, and also affords sufficient space for the inlay without necessitating the cutting away and the weakening of the same.

In carrying out my invention, I make use of the structure illustrated in the accompanying drawings, in which—

Figure 1 represents a side elevation of my improved bag or purse frame. Fig. 2 represents a similar view of the frame, partly in section, showing the manner of securing the inlay to the frame member

without cutting away a portion of the same. Fig. 3 represents an enlarged transverse sectional view taken on lines $x-x$ of Fig. 2.

Similar numerals of reference refer to like parts throughout the specification and drawings.

In the drawings, 1 and 2 indicate the usual pair of frame sections (either channeled or angled) which are pivotally connected at their lower end portions by means of suitable pins or rivets 3, or they may be pivotally connected with each other in any other well known manner. One of said frame sections, as 2, is provided in its upper surface with a suitably-arranged opening for the reception of an extension 4 formed on the catch member 5, and the other frame section, as 1, is provided with the usual nosing or projection, (not shown) forced out from the metal from which said frame section is made, or any other suitable means may be provided, designed to be brought into holding engagement with a suitable indentation or similar means formed in the under side of the catch member, to firmly secure the bag frame sections or members in locked position.

The extension 4 of the catch member 5 passes through a centrally-arranged suitable opening in the central chambered portion 6, extending upwardly from the main body of the bag frame section. In order to hold said catch member in its normal initial position, I employ a suitable torsion spring 7, one end of which is secured to the extension 4 of the catch member 5 and rests against the under side of the frame section, and the other end of which is secured to a spring clip 8 usually consisting of a channel-shaped member forced into the channel-shaped central chambered portion 6 of the frame section and firmly secured thereto by frictional engagement therewith.

It will thus be seen that I have provided a bag frame section having a central chambered portion of the same uniform width as the frame section for securing a bag fastener in position on said chambered portion, said chambered portion being designed also to receive the spring and spring clip, thereby obviating the necessity of cutting away the inlay 9 to which the fabric of the bag body 10 is secured, and weakening said inlay.

Although I have shown the preferred form of my invention, I do not wish to be limited to the exact details of construction shown and described, as obvious modifications thereof may be made by those skilled in the art, and such modifications thereof, not requiring the exercise of the inventive faculties, I consider within the scope and terms of my claim.

10 I claim:

In a purse or bag frame, the combination with a pair of hinged frame sections, each section comprising a main body and an integral pivot member at each end of said main body, said main body portion of each of said frame sections being provided with a central integral chambered portion extending upwardly from said main body member and of the same width as the frame sec-

tion, one of said frame sections in its central integral chambered portion being provided with an opening for the reception of a catch member, a torsion spring located in said integral chambered portion, one end of which is secured to the catch member and a spring-clip located in said integral chambered portion, said spring-clip lying within said integral chambered portion and secured thereto by frictional engagement therewith and to which the other end of said spring is secured.

This specification signed and witnessed this 17th day of April, 1914.

FRANZ A. FULLER.
